UNITED STATES PATENT OFFICE.

MORITZ STEINLIN AND WALTER HOLDERRIGGER, OF ST. GALLEN, SWITZERLAND.

LOOM.

Application filed April 14, 1927, Serial No. 183,835, and in Switzerland April 22, 1926.

The present invention relates to a loom for manufacturing fabrics of willow and other rods and materials which are of longitudinally tapering form, such as nettles, ramie and so forth. Above a sliding beam designed to hold the lower ends of the warps, swing warp guides are provided, capable of being brought into their end-positions alternately by means of rails sliding at right angles to the vertical plane of the loom. Devices are also furnished for enabling the weft-material to be introduced between the swung warps. For beating-up the weft striking-devices, passing between the warp guides, are provided.

A form of construction of the invention is shown in the accompanying drawings, in which:—

Fig. 1 is a front elevation.

Fig. 2 is a view partially in an end elevation and partially in vertical transverse section on opposite sides of the longitudinal center of the loom, the plane of section being such as taken on the line 2—2 (Fig. 1), certain parts being omitted for sake of clearness.

Fig. 3 is a plan, certain parts being omitted for the sake of clearness of the drawing.

Fig. 4 is a part section on the line 4—4 (Fig. 1).

Fig. 5 is a part vertical section taken through the center of the loom.

Fig. 6 is a vertical section on the line 6—6 (Fig. 3) to a larger scale.

Fig. 7 is a plan of Fig. 6.

Fig. 8 is a section on the line 8—8 of Fig. 9. Fig. 9, which is a side elevation of a detail to be hereinafter referred to.

Fig. 10 is a part section on the line 10—10 (Fig. 3).

Fig. 11 is a part section on the line 11—11 (Fig. 3).

Fig. 12 is a part section on the line 12—12 (Fig. 3).

Fig. 13 is a side elevation, drawn on an enlarged scale, of a detail to be subsequently referred to.

Fig. 14 is a plan of Fig. 13.

Fig. 15 is a part section on the line 15—15 (Fig. 3).

Fig. 16 is a plan of Fig. 15.

Fig. 17 is a side elevation, on a larger scale, of a detail to be hereinafter referred to.

Fig. 18 is a front elevation of Fig. 17.

In the constructional example shown, the beam 45, located between the frame uprights

46, 47, is adjustably suspended on cords 48 (only shown in Fig. 1), passing over pulleys 49 and carrying a counterweight 50 corresponding to the weight of the beam 45. On the dovetailed top 51 of the beam 45 there are mounted the riders 54, which are spaced apart by the intervening members 52 and are each furnished with a bore 53 to receive and hold the lower ends of the warps and thereby support the lower portions of the warps and the formed fabric as formed in the weaving operation. The riders are held in position during working of the loom by means of set-screws 55 (Fig. 2). Above the riders, tubes 57, having heads 56, are suspended in forks 58, their lower ends extending to the proximity of the top of the riders 54. The guide-rollers 59 are horizontally slidable, parallel to each other, in guide-grooves 60 provided at the frame uprights 46, 47. The heads 61 of the plungers 62 abut against the guide-rollers 59 and are acted upon by springs 63 (Fig. 2), housed partly in the plungers 62 and partly in the cylindrical casing 64 which receives the latter. The tension of the springs 63 and thus the pressure of the guide-rollers 59, at first against the riders 54 and subsequently against the fabric, can be regulated by levers 65 fulcrumed at 66 to the uprights 46, 47. The levers 65 are coupled to hand-levers 67 (Figs. 2, 17, 18), fulcrumed at 68 to the uprights 46, 47. To maintain the levers 67 in a given position, each is provided with a spring arm 70, having a tooth 69, adapted to engage between the teeth of a rack 71 secured to each upright 46, 47.

For swinging the warp guides, that is to say, the tubes 57, there are provided supporting-rails 72, 73, 74, 75, horizontally slidable in guides 76 on the uprights 46, 47. These rails are furnished with pusher-bars, extending in the direction of motion, whose ends are recessed to receive the tubes 57. The rail 72 is provided with the pushers 77, the rail 73 with the pushers 78, the rail 74 with the pushers 79 and the rail 75 with the pushers 80. The upper faces of the pushers all lie in the same horizontal plane. The ends of the rails 72—75 are provided with outwardly extending hooked arms to which are attached springs 81, whose other end is secured to the brackets 82 extending from the uprights 46, 47. These springs 81 tend to draw the rails 72—75 outwards. The ends 110

of the branches of the cord-system 85-86, secured to the levers 83, 84, are attached to the said hooked arms of the rails 72-75, whereby these rails can be pulled against the action 5 of the springs 81. The branch cords pass over pulleys 87 to the hooked arms of the rails 72-75 in such manner that by descent of the end of the lever 83 attached to the cord 85, the lower rails 73, 75 can at the same 10 time be drawn towards the center of the loom, while by the like movement of the lever 84 the two other rails 72, 74 can be similarly drawn upon, in each case against the action of the springs 81. The actuation of the levers 83, 84, which are fulcrumed on the shaft 89, mounted in bearings 88, is effected by 15 means of cam-disks 90, 91 (Figs. 10, 11), whose cams lie diametrically opposite to each other on the shaft 92, which turns in the bearings 88 and carries the driving-pulley 93.

The weft beating-up levers 95 with the shaft 97, which is mounted on the bearings 96 on the uprights 46, 47, are arranged to rock, so that their heads 98 can pass between 20 the tubes 57 to the center of the loom. For this purpose, on the shaft 97 is mounted a double-armed lever, to whose one arm 99 is attached the upper end of the spring 100, the lower end of which is fastened to the hook 30 101, projecting from the upright 47 (Fig. 2). The other lever-arm 102 (Figs. 3, 15, 16) is jointed to the rod 103, which is connected by a bent lever 104 (Figs. 2, 12) and rod 105 to the bent lever 106, which latter is actuated by 35 the cam-disk 107, having two diametrically opposed cams 108, mounted on the shaft 92.

The weft-material is shot-in by means of a shuttle 110 (Figs. 8, 9), having on its back a clamp 111 to grip the weft. The to and fro 40 motion of the shuttle is imparted by picker-mechanisms, provided upon the uprights 46, 47. These mechanisms have each a casing 115, in which is provided a picker 117 (Figs. 6, 7), furnished with a lining-piece 116 to receive the tip of the shuttle 110. The picker 117 has a pin 118, guided by the slots 119 of the casing 115, which is closed by a cover 120. The spring 121 presses with one end 45 against the picker 117 and with the other end against the stop 122, and its tension can be regulated by means of the set-screw 123. Below the casing 115 is a cam-disk 124, whose cam 125 projects into the path of the lower end of the pin 118. The cam-disk 124 is 50 mounted fast on the shaft 126, which receives motion by means of the bevel gearing 114 from the shaft 127, which itself is driven by the shaft 92 with the aid of chain-gearing 128. 130 are bridges on which the shuttle 60 110 lies between the casings 115 and pusher-bars 77-80 of the rails 72-75; and 131 is an ejector pivotally secured to the part 132, by means of which the weft-material after being shot through the shed is expelled from the 65 clamp 111. One of these ejectors is provided

at each standard, in such manner that only that weft is ejected which is shot from the opposite standard.

The forks 58 are adjustably secured to the rails 135 (Figs. 13, 14), which are supported by the brackets 136 projecting from the frame uprights, and they are held in position by screw-bolts and nuts 133, slideable in grooves 134, in which manner the distances between the individual tubes 57 can be altered as desired. The forks 95 for beating-up the weft and the riders 54 and pusher-bars 77-80 of the rails 72-75 are likewise adjustable as regards distance apart.

Weaving may be carried on as follows:—

The beam 45 is first elevated to such height that the riders 54 enter between the guide-rollers 59. Hereupon the warps are inserted from above through the tubes 57 into the bores 53 of the riders or warp end retainers. The loom can now be started. The cord 85 is first operated and the rails 72, 75 and their pusher-bars 78, 80 will thus be advanced towards the rails 72, 74 and their pusher-bars 77, 79, and the tubes 57 will be swung out into their end-positions, every alternate warp being bent forwardly and the intermediate ones backwardly. During the sliding of the rails 73-75 a shuttle 110, filled with weft, is laid by hand upon the right-hand bridge 130 against the picker 117, brought into its end-position by the operation of the cam 125. Following upon the motion of the pusher-bars 78-80, the cam 125 releases the pin 118 and the shuttle 110 will be impelled by means of the spring 121 to the other side of the loom, traveling between the tubes 57 on the pusher-bars of the rails 72-75. As soon as the weft-material has been shot through the shed, it is 50 expelled from the clamp 111 by the ejector 131 and the weft that has been shot-in is battered or forced down by the heads 98 of the beating-up levers 95 actuated by one of the cams 108. Hereupon the shuttle is provided with new weft-material, and owing to further rotation of the shaft 92 the lever 83 resumes its initial position, the slidden rails under the influence of the springs 81 taking up their original position again, the cords tightening. At the same time the lever 84, actuated by the cam 91, will draw the cords 86 and move the rails 72, 74, whereby their pusher-bars 77, 79 will swing the tubes 57 into their other end-position. The other picker mechanism will now throw back the shuttle 110, with new weft-material, to the opposite side of the loom, in similar manner to that described, and the weft which has been shot-in will then be expelled from the clamp 111 by the ejector at the other standard. After the weft-material has been thus shot-in the weft-beating levers will force this material against the preceding, and at the same time depress the beam 45 through the thickness of the weft-material, whilst the warps 130

will be drawn simultaneously through the tubes 57. When the riders 54 have been depressed beyond the grip of the rollers 59, these will press against the fabric.

5. What we claim is:—

1. A loom for manufacturing cane and like fabrics having a sliding warp carrying beam above which are provided preferably tubular swing guides for the warps, 10 pusher elements, sliding rails movable transversely of the guides and coacting with said pusher elements for swinging the said guides alternately in opposite directions, devices for supplying the weft-material, and mechanism located above the said beam and entering between the warp guides for the purpose of uniformly beating-up the weft-material supplied each time, all substantially as hereinabove described and illustrated.
- 20 2. A loom as claimed in claim 1, in which the warp carrying beam is suspended with the aid of counterweights and is advanced through its depression by the weft beating-up mechanism, all substantially as described.
- 25 3. A loom as claimed in claim 1, in which pressing rollers are provided for the purpose of holding the warps near their place of exit from their guides, substantially as described.
- 30 4. A loom as claimed in claim 1, in which pressing rollers are provided for the purpose of holding the warps near their place of exit from their guides, and in which springs whose tension is regulable are provided for regulating the pressure of said 35 pressing rollers, substantially as described.

5. A loom as claimed in claim 1, in which the members for swinging the warp guides are provided on rails movable in alternate order by actuating means against the action of springs, in such manner that adjacent warp guides are each time swung in opposite directions from their one end-position into the other end-position, all substantially as described. 40

6. A loom as claimed in claim 1, in which there is provided at each end of the warp carrying beam picker mechanism for impelling the shuttle carrying weft material to and fro between the swung warps, substantially as described. 45 50

7. A loom as claimed in claim 1, in which levers are employed to beat-up the weft, said levers being mounted on a common shaft which is actuated by a cam after the weft-material has been shot-in by the shuttle each time, substantially as described. 55

8. A loom as claimed in claim 1, in which the pusher elements employed to push the warp guides are staggered and are carried by rails which are slid able both toward each other and longitudinally, the sliding motion being imparted by means of cams, in such manner that for the purpose of forming the shed, adjacent warp guides are swung each time from one end-position into the other in opposite directions, substantially as described. 60 65

In testimony whereof we affix our signatures.

DR. MORITZ STEINLIN.
